UNITED STATES PATENT OFFICE.

HIRAM C. BURK, OF CLEVELAND, OHIO.

SCRUBBING-MACHINE.

SPECIFICATION forming part of Letters Patent No. 657,584, dated September 11, 1900.

Application filed January 29, 1900. Serial No. 3,141. (No model.)

To all whom it may concern:

Be it known that I, HIRAM C. BURK, a citizen of the United States, and a resident of Cleveland, county of Cuyahoga, State of Ohio, 5 have invented certain new and useful Improvements in Scrubbing-Machines, of which I hereby declare the following to be a full, clear, and exact description, such as will enable others skilled in the art to which it applies to make and use the same.

The object of my invention is to provide mechanical means for scrubbing, polishing, or scouring a floor; and my device consists in the employment of a number of brushes 15 or scrubbing or abrading devices with means for revolving them in groups in opposite directions and for pressing them with a predetermined force against the floor.

The invention also has reference to a compact arrangement of frame and brushes which will make all places about the machine accessible to the action of the brushes.

The invention consists in the combination and arrangement of parts and construction 25 of details, as hereinafter described and shown in the accompanying drawings and specifically pointed out in the claims.

In the accompanying drawings, Figure 1 is a side view of the device. Fig. 2 is a plan view. Fig. 3 is a transverse section on center line of the transverse shaft. Fig. 4 is a plan view of one of the weights. Fig. 5 is an edge view thereof, and Fig. 6 is a sectional view showing the use of abrading devices.

35 In the figures, 1 represents the frame of the machine, to which a handle 2 is pivotally attached, by means of which the machine is pushed over the floor. This handle is adjustable by means of the curved slot 3 and set-screw 4. The frame is rectangular in shape, and between the sides thereof are mounted the heavy driving-wheels 5, which are preferably formed of metal and provided with rubber treads 6, so that the wheels will 45 not slip upon the floor, but will convey movement to the shaft 7, upon which they are mounted, and to the sprocket-wheel 8 between them, which is designed to transmit movement to the gearing that drives the brushes.

50 In the forward portion of the frame is a rectangular space appropriated to the driving-gearing, which may be described as follows:

9 is a transverse shaft mounted upon bearings 10 on either side of the frame. This shaft is provided with the sprocket-wheel 40, 55 to which movement is transmitted by means of the chain 11, passing over the sprocket-wheel 8. On this shaft are also mounted the bevel-gears 31, which face in opposite directions. Underneath the transverse shaft are 60 the vertical shafts 12, which are fixed securely at 13 in the frame. At the lower extremity of each vertical shaft is placed a roller 14, mounted in forked bearings 15 by means of the axles 16. At the upper extremities of 65 the vertical shafts are placed the bevel-pinnions 17, engaging each with one of the bevel-gears 11. A yoke 18 is sleeved over each vertical shaft underneath each pinion and rests upon the roller-bearing underneath it. 70 A clutch 19 in the hub of each pinion engages the hub of the yoke 18 and communicates the movement of the pinion thereto. The brushes 20 are each secured to a heavy plate or weight 21, sufficient to maintain the necessary pressure against the floor, and this weight is provided with a central opening 22, through which project the rollers. Vertical shafts or guide-rods 23, secured to the extremities 75 of the weight, extend upward into the extremities of the yoke, through which they move up and down loosely to accommodate any unevenness in the floor.

It will be seen that with this device there will be no difficulty in maintaining an equal 85 pressure upon the brushes and the degree of pressure can be regulated by providing a plurality of weights, some heavier than others.

The efficiency of this device is much increased by the opposite direction of rotation 90 of the brushes, which turn toward each other, and their lines of rotation intersect at the center of the machine, thus covering all the space gone over thoroughly, throwing the water or suds inwardly instead of spattering it on all 95 sides of the machine. The location of the two front rollers centrally in each group of brushes also serves to bring the brushes into prominence in front and on either side of the machine, so that corners and narrow places become accessible for scrubbing with the machine.

In Fig. 6 are seen slightly-modified forms of the weight and yoke, so that stones or spe-

cially-prepared substances can be employed in the place of brushes for scrubbing or abrading floor-surfaces. In this figure the yoke is brought down at Y and provided with openings X, in which the abrading substances can be placed. The weight 21 is then placed upon them to press them against the floor. The side rods R of the yoke serve as guides for the weight. One-half of the front of the machine is seen in the figure.

Having described my invention, what I claim as new, and desire to secure by Letters Patent, is—

1. In a scrubbing-machine, the combination with the frame, main driving-wheels and centrally-located driving sprocket-wheel, of a transverse shaft located in the front of the machine, provided with a sprocket pinion and chain connecting with the driving sprocket-wheel, vertical shafts mounted underneath the front of the frame, rollers secured to said shafts, yokes sleeved over said shafts, weights encircling said shafts, brushes mounted upon said weights and grouped about each roller, vertical rods or guides passing through said yokes and secured to said weights, and bevel-gearing communicating the movements of said transverse shaft to said yokes, substantially as described.
2. In a scrubbing-machine, a frame, in combination with vertical shafts at the front of the frame provided with rollers at their lower extremities, weights encircling said rollers,

brushes secured to said weights in groups and means for driving said weights and brushes in opposite directions and for affording free vertical movement thereto, consisting of yokes sleeved about the vertical shafts, guide-rods passing through said yokes and weights, bevel-pinions upon the yokes, a transverse shaft, oppositely-faced bevel-gears upon said shaft, and driving mechanism connecting said shaft with the main shaft of the machine, substantially as described.

3. In a scrubbing-machine the combination with a frame and driving mechanism, of a transverse shaft, driven by said driving mechanism, bevel-gears upon said shaft, vertical shafts mounted upon said frame and provided with rollers at their lower extremities, scrubbing devices placed in groups about the said rollers, weights upon the scrubbing devices, yokes upon the vertical shafts, pinions engaging said yokes and the bevel-gears on said transverse shaft, and means for connecting said yokes with the weights and scrubbing devices whereby the movement of said yokes is transmitted to said weights and scrubbing devices, substantially as described.

In testimony whereof I have signed my name to this specification in the presence of two subscribing witnesses.

HIRAM C. BURK.
